Primary Examiner — Jerry Shiuan-Hua Hsu(74) *Attorney, Agent, or Firm* — Suzanne Kikel, Patent Agent(57) **CLAIM**

The ornamental design for a folding safety handrail, as shown and described.

DESCRIPTION

FIG. 1 is a front perspective view of a folding safety handrail in an upright positioning, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view of the folding safety handrail of FIG. 1 in a fold down positioning;

FIG. 9 is a front perspective view thereof, shown in a condition of use, and in an upright positioning; and,

FIG. 10 is a front perspective view thereof, shown in a condition of use, and in a fold down positioning.

The broken lines depicting a truck in FIGS. 9 and 10 illustrate environmental structure that forms no part of the claimed design.
